E. J. DION ET AL

REAMER

Filed May 6, 1922

UNITED STATES PATENT OFFICE.

ENA JAMES DION AND FRED C. DION, OF TURNERS FALLS, MASSACHUSETTS.

REAMER.

Application filed May 6, 1922. Serial No. 558,993.

To all whom it may concern:

Be it known that we, ENA J. DION and FRED C. DION, subjects of the King of Great Britain, residing at Turners Falls, in the county of Franklin and State of Massachusetts, have invented certain new and useful Improvements in Reamers, of which the following is a specification.

This invention relates to reamers, and 10 more particularly to spiral expansion reamers.

An object of the invention is the provision of a spiral reamer that may be expanded or adjusted.

15 A further object is the provision of a reamer formed of a body having tapered slots and tapered blades arranged in said slots, said blades being adjustable longitudinally of the body to expand or contract 20 the reamer.

25 A further object is the provision of a reamer having slots arranged at an angle to its longitudinal axis and blades mounted therein, the blades being provided with spiral cutting edges.

In the accompanying drawings, we have shown one embodiment of the invention. In this showing:

30 Figure 1 is a plan view,

Figure 2 is a side elevation, partly in longitudinal section,

Figure 3 is a transverse sectional view on line 3—3 of Figure 1, and,

35 Figure 4 is a perspective view showing one of the blades removed.

Referring to the drawings, the reference numeral 1 designates the body of the reamer which is provided with a reduced shank 2. This shank is provided with slots 3, arranged at an angle to the longitudinal axis 40 of the tool, the ends of the shanks are provided with reduced threaded portions 4. The intermediate portion of the slots are widened at their upper edges, as indicated at 5.

45 As shown, (see Figure 2) the bottom wall 6 of the slot tapers inwardly toward the outer end of the tool. A blade 7 is adapted to be arranged in each of the tapered slots and these blades are provided with 50 tapered lower faces 8, as shown, corresponding to the taper of the bottom wall 6 of the

slot. The upper portion of the blade is of greater width than the lower portion, being provided with lateral extensions 9 which are received in the upper, widened portions 5 of the slot to furnish a bearing surface. As shown, the blades are straight and are provided with spiral cutting edges 10. The ends of the blades are inclined as at 11, and are adapted to be received in the ends of nuts 12, arranged on the threaded portions of the shank. The engaging faces of these ends as inclined as indicated at 13 to retain the blades in position. The nuts may be provided with suitable openings 14 for the reception of a tool or sharp instrument to permit loosening and tightening of the nuts. A lock nut 15 is arranged adjacent the inner end 12.

In operation, the blades are arranged in the slots in the usual manner and the widened portions 9 of the blades rest in the upper portions 5 of the slots, furnishing an effective bearing to prevent displacement of the blades. The ends of the blades are retained in position in the usual manner by the ends 12. To expand or contract the reamer, the blades are adjusted longitudinally of the slots 3 and the nuts then tightened in the adjusted position. It will be noted that the slots are placed at an angle to the longitudinal axis of the reamer and that straight blades are employed which, however, are provided with spiral cutting edges, producing a spiral expansion reamer.

It is to be understood that the form of our invention herewith shown and described is to be taken as a preferred example of the same, and that various changes in the shape, size, and arrangement of parts may be resorted to without departing from the spirit of the invention or the scope of the subjoined claim.

Having thus described our invention, we claim:

A reamer comprising a body portion having inclined slots and reduced threaded portions adjacent the ends of the slots, the upper portion of each of said slots being of greater width than the lower portion, blades arranged in said slots the lower edges of said blades being inclined corresponding to

the inclination of said slots, said blades being provided with lateral extensions adapted to be received in the upper portions of the slots, and being further provided with 5 spiral cutting edges, said blades being provided with inclined ends, and retaining nuts arranged on the threaded portions of said reamer adjacent the ends of the slots, the

inner faces of each of said retaining nuts being inclined to receive the inclined ends 10 of the blades.

In testimony whereof, we affix our signatures.

ENA JAMES DION.
FRED C. DION.
